UNITED STATES PATENT OFFICE

161,967

FAN

Ford Se Bastian, Chicago, Ill., assignor to Chicago
Electric Manufacturing Company, Chicago, Ill.,
a corporation of Illinois

Application January 14, 1950, Serial No. 7,259

Term of patent 7 years

(Cl. D26—7)

To all whom it may concern:

Be it known that I, Ford Se Bastian, a citizen of the United States, residing in Chicago, Cook County, State of Illinois, have invented a new, original, and ornamental Design for a Fan, of which the following is a specification, reference being had to the accompanying drawing, forming a part thereof:

Fig. 1 is a front perspective view of a fan, showing my design; and

Fig. 2 is a side elevational view thereof.

The dominating features of my design reside in the portions illustrated in solid lines.

I claim:

The ornamental design for a fan, as shown and described.

FORD SE BASTIAN.
